UNITED STATES PATENT OFFICE.

NELSON J. RUSSELL, OF CHICAGO, ILLINOIS.

FUEL-SAVING ATTACHMENT FOR FURNACES.

1,150,456.

Specification of Letters Patent. Patented Aug. 17, 1915.

Application filed March 12, 1915. Serial No. 14,018.

To all whom it may concern:

Be it known that I, NELSON J. RUSSELL, a citizen of the United States, residing at the city of Chicago, in the county of Cook and State of Illinois, have invented certain new and useful Improvements in Fuel-Saving Attachments for Furnaces, of which the following is a specification.

This invention relates to improvements in an attachment to be applied to furnaces, stoves or ranges, but more particularly to the furnaces of power and heating plants, and it consists in certain peculiarities of the construction, novel arrangement and operation of the parts thereof, as will be herein-after more fully set forth and specifically claimed.

The principal object of the invention is to provide efficient means to be applied to furnaces, the term "furnace" being used in a broad enough sense to include stoves, ranges, bake-ovens and the like, for the purpose of supplying atmospheric air and preheating the same as it is supplied to the interior or combustion-chamber of the furnace, to the end, that the supply of air may be heated to a relatively high temperature before being admitted to and distributed within the furnace, and so that its heated oxygen will be utilized to increase from a given amount of fuel, the combustion of the combustible gases, or of the free carbon released during the burning of such fuel, thus attaining the maximum amount of heat units from the fuel, as well as, reducing to a minimum, or preventing the passing off, in the form of smoke, of unconsumed particles of carbon or unburnt gases.

Another object of the invention is to provide an attachment or apparatus of the above described general character, which shall be extremely simple and inexpensive in construction, and easily connected to the furnace, yet strong and durable, with its parts so made that, if desired, it can be mounted on the door of the furnace leading to the fire-box or combustion-chamber, so as to be carried thereby, or that it may be mounted on the wall of the fire-box or said chamber and perform its functions in a satisfactory manner.

Still another object is to provide means for regulating the admission of atmospheric air to the apparatus, of utilizing heat ex-

ternally of the furnace for initially warming or heating the air before or as it passes through the door or wall of the furnace into the inner portion of the attachment, and then affording conduits or passages for the air, whereby they will present a very great area or surface to the inflamed or burning mass of the combustion chamber, so that the air will be superheated, or raised to a very high temperature on its passage through the apparatus and as it is discharged into the furnace.

Numerous other objects and advantages of the invention will be disclosed in the subjoined description and explanation.

In the accompanying drawing, which serves to illustrate the invention—Figure 1 is a plan view of the fuel saving attachment, showing it mounted on a portion of the door of a furnace; Fig. 2 is a vertical longitudinal sectional view taken on line 2—2 of Fig. 1, looking in the direction indicated by the arrows; and Fig. 3 is a cross sectional view partly in elevation taken on line 3—3 of Fig. 2, looking in the direction indicated by the arrows.

Like numerals of reference refer to like parts throughout the different views of the drawing.

The reference numeral 5 designates a portion of the door to the fire-box of a furnace, which may be hinged to the furnace in the ordinary or any preferred way, and said door has an opening 6, which may be of the ordinary kind, and for the usual purpose. Mounted on the outer portion of the door or support 5, which in some instances may be the front plate of the furnace or one of the side walls thereof, and provided with an opening 6, is the outer section or portion 7 of the fuel saving attachment, which portion is contracted toward its outer or free end and is provided at its inner end with an enlarged chamber 8, which chamber or enlarged casing is provided at each of its corners with an apertured lug 9, to rest against the outer surface of the door or support 5, and said lugs provide means for hanging or mounting the casing 8 and its extension 7 on the outside of the said door or support, as will be presently explained. The outer or intake end of the chamber 7 has fitted therein an apertured plug 10, which by preference is frictionally held therein and can

- be removed as desired to permit of another plug having an aperture of greater or less size than that shown in the drawing, so as to admit of more or less atmospheric air to 5 the intake portion of the attachment.
- 10 The inner portion of the attachment consists of a series of spaced apart chambers or hollow casings 11, which are by preference substantially rectangular in shape 15 when viewed from the discharging end of the apparatus, and are made of quite thin metal, so that the air passing through said chambers or casings may be quickly heated by the heat in the fire-box. Owing to the 20 thinness of the metal or material out of which the inner portion of the attachment is made, I may unite the chamber casings or members 11 by means of connections 12, formed integrally therewith, as is clearly 25 shown in Fig. 2 of the drawing, but it is obvious that said connections may be dispensed with, if desired. The chambers or casings 11 are connected in pairs alternately at their upper and lower portions by means 30 of hollow portions or tubular extensions 13, through which the air will pass from one of the chambers or casings 11 to the other. Connected to the upper portion of the innermost casing or chamber 11 by means of 35 a hollow or tubular extension 14, is an expansion chamber or air spreader 15, which is provided at its central portion with a horizontally disposed slot 16, through which the air will be discharged into the fire-box. 40 or combustion chamber of the furnace in the form of a fan-tail sheet, and in a uniform manner, for it will be understood that the cavity of the expansion chamber or spreader 15 at its outer portion is located 45 at an equal distance throughout its entire extent from a given point in the throat or hollow extension 14, which leads from the innermost chamber or casing 11 to said spreader or expansion chamber. The chamber 50 casing 11, adjacent to the door or support 5, is provided at each of its corners with an apertured lug 17, to rest against the inner surface of the door or support 5, said lugs being employed to support the inner portion 55 of the device on the inner surface of the door, for by reference to Figs. 1 and 2 of the drawing, it will be seen that a screw-bolt 18 is extended through the openings in each of the lugs 9 of the outer portion of 60 the attachment, as well as through suitable openings in the door or support 5, and also through the openings in the lugs 17, and are held in place by means of nuts 19, engaging said screw bolts.
- 65 It will be clearly seen by reference to Fig. 1 that the casings or members 11 are reduced successively in size rearwardly from the door or support 5, so that they may not interfere with the opening and closing of the door when the device is mounted there-

on. Of course if the attachment is mounted on the wall of the furnace, this construction need not be adhered to.

By employing my improved fuel saving attachment, it is evident that air at atmospheric pressure will enter through the opening of the plug 10, in the outer end of the intake portion 7 of the attachment, and as it passes through said portion it will be heated or warmed by the external heat of the furnace, which at the furnace door is usually of quite a high temperature, and that the air will pass from the intake portion 7 and chamber 8 thereof through the opening 6 into the chamber 11 adjacent to the door or support 5, and from thence through the circuitous passage or way provided by the hollow members or portions 13 and chambers 11, by means of which passageway and the novel construction thereof, the air will be subjected to the inflammable mass within the firebox and heated to a very high degree of temperature, to be discharged through the opening or slot 16 in the spreader into the fire-box. The damper which controls the draft through the flue of the furnace may be regulated so as to regulate or assist the passage of air through the apparatus, as is obvious.

The advantages of preheating the air draft to a furnace and discharging or dispersing it into or within the furnace or firebox thereof is well-known, and needs no further comment here, and it is also well-known that many forms of apparatus for this purpose have been heretofore employed, and for this reason I do not herein claim means broadly for preheating and distributing air within the furnace, but I do base my claims on the specific construction and arrangement of the parts of my apparatus for said purpose.

It will be observed by reference to Fig. 2 of the drawing, that the hollow connecting chamber 14, is of less size than the device, exclusive of the apertured plugs, in the outer end of the intake member, which construction will to some extent retard the passage of air through the apparatus, so that it can be thoroughly heated, yet in such a manner that continuous circulation or distribution of heated air will be afforded.

Having thus fully described my invention what I claim as new and desire to secure by Letters Patent is—

1. In a fuel saving attachment for furnaces, the combination with a furnace wall having a doorway, of a hinged door therefor, said door having an opening therein leading to the combustion chamber of the furnace, a hollow intake member mounted on the outer surface of said door and provided with a casing encompassing the opening therein externally, means at the outer end of said member to regulate the admis-

sion of air into the same, an inner member consisting of a plurality of successively decreasing communicating spaced apart casings disposed in vertical planes with each other and having means at its inner portion for the discharge of air therefrom into the furnace in a horizontally disposed fan-shape, the said inner member being mounted on the said door with its casing adjacent thereto encompassing the opening within the door, and the casings of said member having alternately at their opposite outer portions communication with one another.

2. In a fuel saving attachment for furnaces, the combination with a door hinged to the furnace and having an opening therein leading to the combustion chamber of the furnace, of a hollow intake member mounted on the outer surface of said door and provided with a casing encompassing the opening thereof, and an inner member consisting of a plurality of successively decreasing spaced apart casings having means at its

inner portion for the discharge of air therefrom into the furnace, the casings thereof having alternately at their opposite outer portions communication with one another, the said inner member being mounted on the said door with its casing adjacent thereto encompassing the opening therein and providing a chamber around said opening, and an expansion chamber, partly spherical in shape and mounted on the inner end of said inner member and communicating therewith through an opening of less area than the other openings leading from one casing to the other, the said expansion chamber having a horizontally disposed slot extended from one side of its vertical wall to the other side thereof, to the end, that the passage of air through said slot will be discharged in a fan-shaped horizontal sheet.

NELSON J. RUSSELL.
